SHINGLE UNIT AND ROOF BUILT
THEREFROM

William L. Rowe, New York, N. Y., assignor to
Johns-Manville Corporation, New York, N. Y.,
a corporation of New York

Application March 16, 1931, Serial No. 522,817

15 Claims. (Cl. 108—9)

This invention relates to a shingle unit and a roof or side wall structure built therefrom.

One object of the invention is to provide a shingle unit which can be laid in the exposed side-lap or Dutch lap mode. A further object is to provide units for this purpose which will be self-spacing in respect to the vertical overlap and the horizontal overlap. Another object is to provide a shingle unit of this nature in which the exposed edges may be the rough, moulded or natural edge of a tile, sheet, or part of a slab, natural or artificial, for example, a sheet of a plastic composite, such as a bituminous or cement-integrated asbestos or other fibrous sheet. A further object is to provide, in these relations and for these purposes, a shingle unit which can be laid without loss of any useful function either from left to right or from right to left, and which can be preformed to space a lateral overlap of two or more different fractional parts of each shingle unit; for example, which will provide for an exposure of two-thirds of the lateral dimension of each unit, or for three-fourths of the lateral dimension of each unit when laid, or of any fraction between said values. A further object is to provide a shingle unit, tile, slab or sheet with preformed edges and perforations in relatively exact relation to each other, so that full reliance may be placed upon the dimensional accuracy of relationship of one unit to another indicated and measured thereby.

The invention will be explained, for illustration only, with the aid of the accompanying drawings, in which:

Fig. 1 is a detail in perspective of a part of a roof laid with shingle units in one mode according to this invention;

Fig. 2 is a plan view of one of the units turned for laying in progression from the left to the right;

Fig. 3 is a plan view of one of the shingle units turned into position for laying in progression from right to left;

Fig. 4 is a section on the line 4—4 of Fig. 1, showing a preferred form of storm anchor or clip relied upon in connection with the construction of a roof;

Fig. 5 is a diagram in plan showing a detail of the construction of a roof from left to right with one proportion of overlap;

Fig. 6 is a corresponding diagram in plan showing a detail of the construction of a roof from right to left with another proportion of overlap;

Fig. 7 is a similar diagram showing a roof of a modified unit laid from right to left;

Fig. 8 is a plan of one of the modified units; Fig. 9 is a plan showing a preferred form of starter strip; and

Fig. 10 shows a detail of a roof laid in an overlap of one-third of the unit width of the shingle 60 unit of Fig. 2.

Referring now to Figs. 2 and 3, shingle units A for the desired purpose may be constructed of square slabs or sheets, indicated in Fig. 3 by the rectangle 1, having if desired the natural edges, 65 by which I refer to irregular or rough edges 2, 3, resulting from transverse pressure during manufacture. Such a slab, plate or tile is a structure having an axis of symmetry on the line a—a, and according to this invention this axis of symmetry 70 remains the axis of symmetry in the completed structure. For purposes to be explained the edges 1, 1, and the corner between them are removed from the plate by severing by a shearing, die-cutting or sawing operation, so as to provide 75 an edge 6 accurately perpendicular to an edge 7, which edges in turn are respectively equidistant from the mean position of the edge 2 and the mean position of the edge 3; the angle between the edges 7 and 6 is truncated (if desired, by die cutting in one operation with the formation of edges 6 and 7) to form an edge 8 perpendicular to the axis a—a and at a suitable distance from the intersection of the sides 6 and 7 prolonged.

The accurate cut edges 6, 7 and 8 are now relied upon (or formed by punching in the same operation, thereby) to pre-position the places of certain preformed perforations, which perforations are arranged in symmetry to the axis a—a. Of these perforations a hole for the anchorage 90 clip 10, Fig. 4 may be central on the axis a—a and therefore equidistant from the edges 6, 7 and 2, 3, as shown at b, Fig. 3. The remaining perforations comprise a pair of nail holes in the corner between the edge 7 and the edge 2, as 95 shown at 12 and 13, and a similar pair of nail holes in the corner between the side 6 and the side 3, as shown at 14, 15. The respective holes 12, 13 and 14, 15 are accurately spaced with respect to distance from the respective sides 7 and 6 and distance from the truncated edge 8.

Referring to Figs. 1, 5 and 6, let us suppose one of the shingle units to be placed as shown in Fig. 2, with its edge 2 downward and the edge 3 to the left. If, then, another shingle unit in the same position be placed with the nail hole 15 just over the edge of the truncated edge 8, as shown in Fig. 1, the bottom edges of the shingle units being coincident, the position of the hole 15 is such as to predetermine an overlap of a predetermined frac-

tion, for example, one-fourth of the lateral dimension of the shingle unit. But if the hole 14 were placed so that the nail through it would be in contact with the edge 8, the overlap might be of 5 another predetermined fraction of the width, for example, more than one-third of the lateral dimension of the shingle unit. If now the shingle units are turned to the position of Fig. 3 with the edge 3 down and the cut edge 6 to the left, another 10 similarly placed shingle unit might be laid upon it to the left and registered so as to laterally overlap the truncated edge 8 when a nail through one of the holes 12 or 13 is in contact with the edge 8 of the first shingle unit with the same accuracy, 15 to predetermine one or the other of the different proportional overlaps for which the nail holes 12 and 13 provide fastening holes clear of the underlying shingle.

Referring now to Figs. 7 and 8, the improved 20 units do not necessarily include adjacent rough edges. For example, a unit B may be cut from one of the slabs 1 on lines 2^a and 3^a removing the rough edges, the sides 6^a, 7^a and 8^a being formed as above described, and the nail and anchorage 25 holes 13, 15 and b formed as above described. Whether or not the rough edges are retained, I may space the holes 12^a and 14^a further from the adjacent edges than in the case of units A, so that, as shown in Fig. 7, these holes may gauge 30 an overlap by a nail in them registering with the truncated edge 8 or 8^a when the overlap is at a predetermined fraction of the unit width; for example, one-third of that width, as shown in Fig. 7.

35 Likewise, referring now to Figs. 5 and 6, whether the shingle units are laid from left to right or from right to left, and whether they are rotated to the position of Fig. 2 or to the position of Fig. 3, that pair of nail holes not utilized for gauging 40 and fastening down the upper end of the shingle presents by its upper member a hole for a nail clear of the top edge of the previously laid course which may if desired gauge the vertical overlap between courses of the shingle units. For example, the nails shown at n, Fig. 1, are placed in 45 holes 12 and against the top edges 6 of shingle units of the previous course to gauge and fix the vertical overlap; whereas the nails n' in the nail holes 15 driven in contact with the truncated 50 edges 8 of the next previous shingle to the left in the same course laterally gauge the position of the last-placed shingle unit. In the instance shown in Fig. 1 the overlap is one-fourth of the lateral dimension of the shingle units; whereas if the 55 nails n' had been placed in the holes 14 and the nails driven clear of the edges 8, the overlap might have been one-third of the width of a unit. Thus the side lap may well be independent of the 60 gauging permitted by the nail holes, being the function of a starter shingle of predetermined width mentioned below, shingles of a following course abutting against the corners of shingles of a preceding course to determine the lap, as appears at g, Fig. 1. See, for example, Fig. 10, 65 where the overlap is one-third. But in this case the shingle units have been laid from right to left, and the nails are in the holes 12.

In either lay of the shingles, that is, from left to right or from right to left, or with one-fourth 70 overlap to one-third or greater overlap, the bottom edges of the shingle units are in alignment. This may be produced and aided by the application of a storm clip entering the hole b, preferably of a kind having an element to predetermine the 75 alignment between an exterior shingle unit con-

taining the hole b and the next shingle under it, as will be clear from Fig. 1, Fig. 4, Fig. 5, or Fig. 6. The lateral overlap of the shingle units provides the two outer plies of the structure shown in Fig. 4, whereas the vertical overlap over a shingle of the previous course provides the inner ply. A typical vertical section of this structure, as shown in Fig. 4, comprises the roof deck W, may comprise a paper or felt layer f, and comprises an inner ply of the shingle units at p¹, an intermediate ply at p², and an outer ply at p³. The preferred form 8 of anchorage connection, as shown at 10, has a top 11 with a hook 12 to enter the hole b, the clip 10 extending to and downward past the coincident edges 2 or 3 of the shingle unit of the top ply and past the edges 2 or 3 of the shingle unit of ply p² under it, ending in a base portion 14 entering under the shingle unit of ply p² and over the shingle unit of ply p¹. I do not herein claim the 9 clip 10 which is the subject of my application Serial No. 522,814, filed of even date herewith, except in combination with the present devices. 9

A roof laid in the Dutch or side and top lap with the shingle units of this application may contain contributing constructions, for example, a 10 cant strip or the eaves-starter strips 20, Figs. 1 and 9, and fractional shingle units of suitable width for use at the beginning edge of each course, as shown at 21 and 22, Fig. 5. The strips 20 may have a slant 24 of which the lateral width 10 from the adjacent end is x, a suitable fraction of the width of one of the units, such as one-fourth; and a notch at 25, the distance y of which from the end is another fraction, such as one-third, of the unit width. Thus the starter strips 20 can 11 be overlapped with the aid of the slant end or of the notch in accurate position to gauge the overlap of subsequent courses of units A, as shown at g, Fig. 1.

11 It will be observed that when laying in sequence shingle units on any course, the position of the shingle is fixed by abutment against a lateral edge of the shingle laid on the next lower course, as well as by the position of the nail n' in its appropriate hole for the desired overlap. It will 12 be observed that by use of the clips 10 firm anchorage of the shingles is secured without perforation of the underlying shingle of the three-ply overlap or of the intermediate shingle of this overlap, and that insertion of the clip does not 13 imply lifting the free end or corner of a shingle 14 applied by nailing.

The provision for building a roof by side overlap shingles with the overlaps going in either 1 direction is of architectural importance. The 1 shingles may be laid so as to avoid having their butt ends or free sides turned toward the direction from which the prevailing winds blow; or, where winds are not expected, the side overlaps may be exposed in the best direction to secure 1 edges or the shadows of edges contributing to the appearance of the house from the usual point of view.

I claim:

1. Shingle unit adapted to be laid in horizontal 1 rows in side-lapped relation comprising a slab having four sides including two adjacent edges adapted to be exposed, two opposite edges lying at like angles to a diagonal line of symmetry, and 1 symmetrically placed nail holes near said opposite edges, the slab material adjacent to their geometrical meeting point of the lines of said opposite edges being removed to facilitate nail fastening of the corner of the adjacent overlying 1 similar slab through one of said nail holes therein. 1

2. Shingle unit adapted to be laid in side-lapped relation comprising a slab having a portion to be exposed having edges at right angles to each other equiangularly disposed to opposite straight edges at an angle to each other, a truncated edge between said straight edges, and pre-formed nail holes near said straight edges and at predetermined equal distances respectively from said straight edges and from said truncated edge, whereby said shingle unit may be laid in underlapped relation with its truncated corner to the right or left in gauging registry with a similarly positioned overlapped unit. 80
3. Shingle unit adapted to be laid in side-lapped relation comprising a slab having a portion to be exposed having edges at right angles to each other equiangularly disposed to opposite straight edges at an angle to each other, a truncated edge between said straight edges, and pre-formed pairs of equally spaced nail holes near said straight edges and at predetermined equal distances respectively from said straight edges and from said truncated edge, whereby said shingle unit may be laid in a laterally greater or less underlapped relation with its truncated corner to the right or left in gauging registry with one or the other of a pair of the holes in a similarly positioned overlapped unit. 85
4. Roof made up of a deck and slab shingle units in side and end overlapping relation, said units having truncated corners between adjacent cut edges in gauging proximity to a nail driven into the deck through a hole near one of the cut edges of an overlapping shingle, said overlapping shingle having a nail in a hole near its other cut edge in gauging proximity to the top edge of a shingle unit of a previous course. 90
5. Roof made up of a deck and slab shingle units in side and end overlapping relation, said units having truncated corners between adjacent cut edges in proximity to a nail driven into the deck through a hole near one of the cut edges of an overlapping shingle, said overlapping shingle having a nail in a hole near its other cut edge in proximity to the top edge of a shingle unit of a previous course, in combination with means uniting the otherwise free corner of one or more of the shingle units to the next unit of the same course. 95
6. Roof made up of a deck and slab shingle units in side and end overlapping relation, said units having truncated corners between adjacent cut edges and nail holes symmetrically placed in relation to said truncated corners, said corners being in proximity to a nail driven into the deck through a hole near one of the cut edges of an overlapping shingle, said overlapping shingle having a nail in the hole near its other cut edge in proximity to the top edge of a shingle unit of a previous course. 100
7. Roof made up of a deck and slab shingle units in side and end overlapping relation, said units having truncated corners between adjacent cut edges and nail holes symmetrically placed in relation to said truncated corners, said corners being in gauging proximity to a nail driven into the deck through a hole near one of the cut edges of an overlapping shingle, said overlapping shingle having a nail in the hole near its other cut edge in gauging proximity to the top edge of a shingle unit of a previous course, in combination with a clip passing over the edges of and uniting the otherwise free corner of one or more of the shingle units to the next unit of the same course. 105
8. Shingle unit adapted to be laid in side-lapped relation with similar units to provide either a right-handed or left-handed overlap, comprising a slab having a substantially rectangular shape with the major portions of its edges lying parallel and at right angles to each other, the material of the slab being removed adjoining one corner to provide a gauging portion for an adjoining unit in overlapping relation therewith, the slab having a pair of openings disposed adjoining said corner but at respectively different distances from said corner, the opening nearer the corner being adapted to receive a fastening element located in relation to an adjoining unit when a smaller lateral overlap is desired and the other opening of the pair being similarly adapted to receive such an element when a larger overlap is desired, said slab having other openings arranged at other corners to receive fastening means to cooperate in securing the unit to a roof, whereby the lateral overlap of the units may be varied. 110
9. Shingle unit adapted to be laid in side-lapped relation comprising a slab of substantially rectangular form, said slab having openings for fastening elements adjoining three of its corners, the material of the slab being removed adjoining the fourth corner to provide a gauging portion, so that portion may underlap the edge of a similar unit and may register with an opening therein to permit application of the shingles to a deck with one of a plurality of preselected overlaps. 115
10. Shingle unit adapted to be laid in a side-lapped relationship with similar units either from left to right or right to left, comprising a slab of substantially rectangular outline, the material of the slab being removed adjoining one corner to provide a gauging portion within its rectangular outline, said slab also having adjacent its side edges which extend to said corner nail holes which are located symmetrically with relation to a diagonal line extending from said corner to the opposite corner, said gauging portion and nail holes being so constructed and arranged that the gauging portion may underlap the edge of a similar unit and may register with a hole therein to permit application of the shingles to a deck with either of two preselected overlaps when laying either from left to right or right to left. 120
11. Shingle unit adapted to be laid in side-lapped relation, comprising a slab of substantially rectangular form, the slab having at least two sides affording straight edge portions extending between the main planar faces of the slab, said slab having openings for fastening elements adjoining three of its corners, said openings having walls providing edges of the material extending between the main planar surfaces, the openings adjoining diagonally opposite corners being disposed symmetrically in relation to a diagonal line extending between the other pair of diagonally opposite corners, the fourth corner at one end of said line having material removed therefrom to afford gauging means extending between the main planar surfaces, said gauging means being symmetrically disposed in relation to said diagonal line and shaped to register with edges of the material of similar units to permit the units to be laid in self-gauging relationship with either one of two selected degrees of overlap when laid either from left to right or right to left. 125
12. Single units of the type comprising substantially rectangular slabs adapted to be laid in side overlapping relationship, the slabs having in opposite corners openings which are disposed 130
13. Shingle unit adapted to be laid in side-lapped relation with similar units to provide either a right-handed or left-handed overlap, comprising a slab having a substantially rectangular shape with the major portions of its edges lying parallel and at right angles to each other, the material of the slab being removed adjoining one corner to provide a gauging portion for an adjoining unit in overlapping relation therewith, the slab having a pair of openings disposed adjoining said corner but at respectively different distances from said corner, the opening nearer the corner being adapted to receive a fastening element located in relation to an adjoining unit when a smaller lateral overlap is desired and the other opening of the pair being similarly adapted to receive such an element when a larger overlap is desired, said slab having other openings arranged at other corners to receive fastening means to cooperate in securing the unit to a roof, whereby the lateral overlap of the units may be varied. 135
14. Shingle unit adapted to be laid in side-lapped relation with similar units to provide either a right-handed or left-handed overlap, comprising a slab having a substantially rectangular shape with the major portions of its edges lying parallel and at right angles to each other, the material of the slab being removed adjoining one corner to provide a gauging portion for an adjoining unit in overlapping relation therewith, the slab having a pair of openings disposed adjoining said corner but at respectively different distances from said corner, the opening nearer the corner being adapted to receive a fastening element located in relation to an adjoining unit when a smaller lateral overlap is desired and the other opening of the pair being similarly adapted to receive such an element when a larger overlap is desired, said slab having other openings arranged at other corners to receive fastening means to cooperate in securing the unit to a roof, whereby the lateral overlap of the units may be varied. 140
15. Shingle unit adapted to be laid in side-lapped relation with similar units to provide either a right-handed or left-handed overlap, comprising a slab having a substantially rectangular shape with the major portions of its edges lying parallel and at right angles to each other, the material of the slab being removed adjoining one corner to provide a gauging portion for an adjoining unit in overlapping relation therewith, the slab having a pair of openings disposed adjoining said corner but at respectively different distances from said corner, the opening nearer the corner being adapted to receive a fastening element located in relation to an adjoining unit when a smaller lateral overlap is desired and the other opening of the pair being similarly adapted to receive such an element when a larger overlap is desired, said slab having other openings arranged at other corners to receive fastening means to cooperate in securing the unit to a roof, whereby the lateral overlap of the units may be varied. 145

symmetrically to each other in relation to diagonal lines extending between the other opposite corners, the edges of the openings being adapted to cooperate with fastening elements to hold the slabs in position, the corners at corresponding ends of said diagonal lines having material removed to form gauging edges, said edges being arranged to locate and maintain the units with either of two preselected degrees of overlap when laying the units either from left to right or from right to left.

13. Shingle units of the type comprising substantially rectangular slabs adapted to be laid in side overlapping relationship, the slabs having in opposite corners openings which are disposed symmetrically to each other in relation to diagonal lines extending between the other opposite corners, the edges of the openings being adapted to cooperate with fastening elements to hold the slabs in position, the units having material removed at and near corresponding ends of said lines to form gauging edges, said edges serving to locate and maintain the units with either of two preselected degrees of overlap when over-

25

lapping either from left to right or from right to left.

14. Shingle units of the type comprising substantially rectangular slabs adapted to be laid in side overlapping relationship, the slabs having in opposite corners openings which are disposed symmetrically to each other in relation to diagonal lines extending between the other opposite corners, the units having material removed at and near corresponding ends of said lines to form gauging edges which determine either of two preselected degrees of overlap when laying the units from right to left or from left to right with fastening elements extending through said openings.

15. A shingle of substantially rectangular form symmetrical in respect to one diagonal, said shingle having a nail hole adjacent one corner and intersected by said diagonal, and a cut-away corner portion at the opposite end of said diagonal, the shingle also having nail holes adjacent the other two corners symmetrically disposed in relation to said diagonal.
